[57] CLAIM

The ornamental design for an aerodynamic spoiler for
attachment to an upper rear portion of an automobile, as
shown and described.

DESCRIPTION

FIG. 1 is a top plan view of an aerodynamic spoiler for
attachment to an upper rear portion of an automobile,
showing our new design;

FIG. 2 is an enlarged top perspective view thereof;

FIG. 3 is an enlarged end perspective view thereof;

FIG. 4 is an enlarged top plan view thereof taken from
a different angle than as shown in FIG. 1;

FIG. 5 is an enlarged end elevational view thereof;

FIG. 6 is an enlarged end elevational view thereof op-

posite to that shown in FIG. 5; and

FIG. 7 is a greatly enlarged cross-sectional view thereof
taken along line 7—7 in FIG. 4.**FIG.1****FIG.2****FIG.3****FIG.4****FIG.5****FIG.6****FIG.7**
